RADIO BEACON SYSTEM

Walter Max Hahnemann, Berlin, Germany, assignor to C. Lorenz Aktiengesellschaft, Berlin-Tempelhof, Germany, a company

Application May 25, 1938, Serial No. 209,973
In Germany May 25, 1937

5 Claims. (Cl. 250—11)

The present invention relates to radio beacons adapted to produce guiding course lines for vehicles and the like, and consists in certain features of novelty explained in the following description and pointed out in the appended claims, reference being made to the accompanying drawings in which—

Fig. 1 is a diagrammatical representation of the radiation pattern obtained by radio beacon transmitters adapted to produce a straight course line; Fig. 2 is a diagram showing radiation patterns for obtaining a bent course line; Fig. 3 shows a plurality of course lines produced according to the invention; while Fig. 4 is a plan explanatory for the invention, and Fig. 5 shows diagrammatically an arrangement of a transmitting beacon in accordance with my invention.

Radio beacon arrangements are known which produce guiding course lines by the utility of one radiating antenna which is continuously fed by a high frequency generator and two reflecting means which are alternately keyed in such manner that one reflector is effective during the ineffectiveness of the other reflector. The line of equal field intensity thus obtained represents the guiding course line. This condition is illustrated in Fig. 1 by way of an example. The radiating dipole D is continuously fed by a high frequency generator which is modulated with a predetermined tone-frequency. The reflectors R1 and R2 are alternately keyed in accordance with the dash-dot, or the A-N-rhythm in such manner that one reflector is rendered effective whilst the second reflector is rendered ineffective. The two radiation patterns A1 and A2 are thus alternately produced, and the two guiding lines L1 and L2 are obtained by comparison between the amplitudes of the keyed signals of different kind. In cases that the system presents symmetric structure, the two guiding lines L1 and L2 form one single straight line. It is also possible to provide any optional angular relation between the two guiding lines L1 and L2 by deliberately unbalancing the aforesaid symmetry which may be accomplished by exciting the two reflectors out of phase which expedient permits the radiation to be directed at will toward any desired point or position.

The Fig. 2 shows the last mentioned arrangement, according to which the radiating dipole is continuously supplied and the reflecting means R1 and R2 are alternately rendered effective and ineffective exactly in the manner heretofore described. The phases of the reflector exciting voltages may be adjusted at any desired rate so

as to obtain the desired unsymmetry of the radiation patterns A1 and A2 relative to each other. The straight 180 degree relation between the two guiding lines L1 and L2 is then replaced by an obtuse angle.

The radiation of more than two guiding course lines from one single point is frequently required. This problem is solved according to the present invention by providing a radio beacon system 10 which permits any desired number of course lines to be radiated over an antenna system using one single transmitter only. The novel system comprises one continuously fed radiating dipole D adapted to cooperate with any desired number of reflector sets R1, R2, and R1', R2' which are alternately rendered effective. According to a further feature of the invention either a particular keying frequency, or a distinctive high frequency or even tone-frequency 15 is allotted to each set of reflectors for the purpose of distinguishing the separate course lines thus produced. The direction of the individual course lines is determined by correspondingly adjusting the phases at which the reflectors are 20 excited by any known means.

The operation of the new system according to the invention is hereinafter more precisely disclosed in conjunction with one embodiment shown in Fig. 3, and the structural diagram of 25 Fig. 5, which by way of an example illustrates an arrangement for producing four different course lines. A radiating dipole D is continuously fed from a high frequency generator TR. Two reflecting means R1 and R2 forming one 30 set of reflectors are allotted to said dipole. A further set of reflectors independent of the first mentioned set and comprising the reflecting means R1' and R2' is also allotted to the radiating dipole D so that two separate systems are 35 obtained, that is, one system comprising the radiating dipole D and the reflecting means R1 and R2, and a second system likewise comprising said dipole D and also the reflecting means R1' and R2'. In cases that the first mentioned system, i. e. D, R1 and R2, is rendered effective, the directive diagrams A1 and A2 and thus the course lines L1 and L2 are obtained, while the effectiveness of the second system, that is, D, R1' and R2', produces the directive diagrams A1' and A2' and the resulting course lines L1' and L2'. These two systems are alternately rendered operative by known means such as switching device U, and a switch S1, in such manner that one system transmits over a period of one minute, for example, during which interval the sec-

ond system remains inactive, whereupon the second system operates for one minute, in which time the first mentioned system remains ineffective.

It has been proposed according to one feature of the present invention for the purpose of distinguishing from one another the different course lines produced by the two alternately effective systems to allot thereto either distinctive high frequencies, that is, various wavelengths, or distinctive modulation frequencies, i. e. specific characterization tones, or even different keying frequencies, but the simultaneous utility of more than one of the above mentioned markings of distinction is also within the scope of this invention. The discrimination between the separate course lines is effected in the receiving position and this will be accomplished in connection with the first mentioned method by accordingly tuning the high-frequency portion of the receiver, while on applying the second expedient this distinction is performed by chains of filters forming part of the low-frequency portion of the receiver. The corresponding discrimination in cases of employing the last mentioned method is accomplished in a simple manner by means of acoustic comparison.

It has already been pointed out in the foregoing that the particular advantage involved by the present invention consists in the possibility of producing a plurality of course lines by means of one single high frequency transmitter. In order to obtain the aforementioned course line distinction, a switching equipment U is provided for cooperation with said transmitter, this equipment being adapted to alternately apply thereto either different high frequency oscillations, or different modulation frequencies from generators M₁, M₂, or different keying frequencies from generator G. Moreover, additional switching means S₁ are provided which during the effectiveness of one reflector system render the remaining systems ineffective. This measure may suitably be effectuated by making the switching equipment of the transmitter dependent upon the switching means which during the operation of one reflector system render all remaining systems inoperative. A conjoint cam-controlled device may, for example, be used for this operation.

According to still another feature of the invention, the separate reflecting means of reflector systems transiently in state of rest are not necessarily to be rendered ineffective during the operation of one particular reflector system. On the contrary, individual reflecting means may be maintained effective so as to assist in producing the necessary directive characteristics for obtaining radiation toward a given direction.

In connection with the embodiment shown in Fig. 3 it should be observed that the dash-dotted circular radiation pattern of the radiating dipole D during ineffectiveness of the reflectors is dimensioned so as to intersect all points of intersection between the entire number of directive characteristics, in order to secure keying free of crash noises.

An arrangement of the new radio beacon system is illustrated in Fig. 5 in which there is shown a radiating dipole D which is continuously fed from the high frequency transmitter Tr over the feeder line L. At either side of the dipole D there are provided the reflectors R₁ and R₂ which together form a continuous guiding system. Further reflectors R_{1'} and R_{2'}

which likewise form a second continuous guiding system are located at a given angle to the first mentioned system R₁, R₂. Each of the reflectors includes keying means K₁, K₂ and K_{1'}, K_{2'}, respectively. The keying means K₁ and K₂ on the one hand and the keying means K_{1'} and K_{2'} on the other hand are coupled with one another and are controlled over the line L₁ and L₂, respectively, from the device G which generates a keying frequency. A switching device U has for its object to alternately render effective the reflector-systems R₁, R₂, and R_{1'}, R_{2'}, respectively, for which purpose a switch S₁ is mechanically coupled with the switching device U. The switch S₁ in one position causes keying means K₁, K₂ of the reflector system R₁ and R₂ to be controlled over the line L₁ from keying device G, while in the other position the keying means K_{1'}, K_{2'} of reflector system R_{1'}, R_{2'} are controlled over line L₂ from G. If asymmetric patterns are desired, as shown in Figs. 2 and 3, such patterns may readily be secured by adjusting the phases of excitation of the reflectors in any known manner. If, for example, these reflectors are parasitic reflectors as shown in Fig. 5, central inductance F may be adjusted to effect such tuning, as is usual in the so-called "Lorenz" type system. A further switch S₂ which is adapted to cooperate with the aforementioned switch S₁ serves for changing keying frequency being produced by the generator G so that a different keying frequency is used on the separate course lines. This may be accomplished in any known manner, e. g. by varying the release time of relays if the keying device G is of the relay interrupter type or by varying the speed of rotation of a motor if this generator G is of the motor driven cam controlled type. Finally, a third switch S₃ likewise mechanically coupled with the switching device U and the aforementioned two switches has for its object to alternately apply the means M₁ and M₂ to the high frequency transmitter Tr. These means M₁ and M₂ may be tone frequency generators producing different tone frequencies by means of which the transmitter Tr is modulated in dependency upon the position of the switches. On the other hand, the means M₁ and M₂ may be devices adapted to change the carrier frequency of the transmitter Tr, that is, the wavelength produced by said transmitter. For example, devices M₁ and M₂ may be carrier frequency sources of different frequency for supplying different carrier frequencies to transmitter Tr.

The invention is by no means restricted to the arrangement for producing four guiding course lines as described in conjunction with Figs. 3 and 5. On the contrary, any desired number of reflector systems as above described may be allotted to a radiating dipole so as to produce six, eight, ten or more guiding course lines. A given distinction such as a predetermined wavelength modulating frequency or keying frequency is to be allotted to each course line.

Geographical and atmospheric conditions frequently obstruct the possibility for employing a throughout straight course line between two air ports, in which cases it will be necessary to provide a more or less zigzag-shaped routing and to accordingly simulating the radio beacon radiation. One example for this condition is shown in Fig. 4. It will be assumed that it is impossible to fly on a straight course line from point A to point B so that the vehicle must be routed via the points C and D' which may be auxiliary land-

ing grounds, for example. In order to obtain a guiding course line which corresponds to the route in question, and in accordance with still a further feature of the invention, individual guiding ray transmitters of the type above described are located at the points or landing grounds C and D' for producing radiations having the desired angular relation to one another. The angle of radiation from each transmitter is adjustable by accordingly selecting the relative phases for keying the appertaining reflectors.

What is claimed is:

1. A radio beacon transmitter system comprising a radiating dipole antenna, a high frequency generator for continuously feeding said antenna, a plurality of reflecting means arranged about said dipole and combined to form several individual reflector systems for providing separate angularly related guiding course lines, and means for rendering said reflector systems alternately effective and ineffective.

2. A radio beacon transmitter system as defined in claim 1, further comprising means for transmitting a different given high frequency from said dipole for each of said alternately effective reflector systems.

3. A radio beacon transmitter system as defined in claim 1, further comprising means for providing a different specific modulating tone-frequency to said generator for each of said alternately effective reflector systems.

4. A radio beacon transmitter system as defined in claim 1, further comprising means for switching a different particular keying frequency to control each of said alternately effective reflector systems.

5. A radio beacon transmitter system comprising a high frequency generator, a radiating dipole continuously fed by said high frequency generator and adapted to produce a circular radiating pattern, a plurality of reflecting means arranged about said dipole and to form several individual angularly related reflector systems, means for rendering said reflector systems alternately effective and ineffective for producing separate angularly related guiding course lines, and means for allotting to each of said alternately effective reflector systems a distinguishing signal characteristic.

WALTER MAX HAHNEMANN.
